ARTICLE FORMING MACHINE

Ben K. Ford, Westfield, N. J., assignor to Western Electric Company, Incorporated, New York, N. Y., a corporation of New York

Application October 11, 1938, Serial No. 234,371

7 Claims. (Cl. 66—9)

This invention relates to an article forming machine and more particularly to a knitting machine for forming a covering on an insulated electrical conductor.

In various phases of the electrical art it is desirable in many instances to be able to distinguish one electrical conductor from another in dark or poorly lighted places where distinguishing characteristics are not visible.

An object of the invention is to provide a simple, efficient and practical machine for forming identifying coverings on articles.

With these and other objects in view, the invention comprises a knitting machine having a winding unit driven in synchronism therewith to apply a spiral winding of a strand about a conductor while advancing and subsequently knitting a covering thereon.

Other objects and advantages will be found in the following detailed description when taken in conjunction with the accompanying drawing, wherein

Fig. 1 is a front elevational view of the machine, portions thereof being shown in section, and

Fig. 2 is a fragmentary view illustrating the article formed by the machine.

The knitting machine disclosed is of a general conventional structure, of which only sufficient is shown in the drawing to enable a clear understanding of the novelty embodying the invention. This machine is patterned after the one shown in my Patent No. 2,126,250 issued August 9, 1938.

A stationary frame 10 is mounted upon a suitable support (not shown) and is apertured adjacent its center with a tubular sleeve portion 11 integral therewith and extending downwardly, as shown in Fig. 1. A hollow or tubular shaft 12 is rotatably disposed in the sleeve 11 and has a flanged upper portion 13 which rests upon the upper surface of the housing. The lower end of the shaft 12 has fixed thereto a bevelled gear 15 which interengages a similar gear 16 mounted upon a power shaft 17 which is driven by any suitable power means (not shown).

A needle carrier 20, having longitudinally extending slots for receiving needles 21, extends for a portion of its length downwardly into the shaft 12 and is secured thereto by a nut 23 disposed in threaded engagement with the upper end of the shaft and positioned to engage an annular projection 24 of the needle carrier.

A lever supporting bracket 28 fixed to the needle carrier has elements 29 disposed at selective

spaced positions about the needle carrier to pivotally support needle actuating levers 30 in positions in radial alignment with the needle slots in the needle carrier. The levers 30 are operatively connected to the needles, as indicated at 31, and have their lower extensions controlled by associated cams 33 and 34 mounted upon the frame 10 to cause actuation of the needles in predetermined sequence. Guides 35, slotted to receive the lower extensions of the levers 30, serve to prevent the levers from dragging.

Threads 40 are fed to the needles from supplies (not shown) between friction discs 41, suitably positioned upon a bracket 42, mounted upon one of a pair of uprights 43. The threads 40 are further directed to their respective guides 44 and through the apertures in the lower ends thereof. The thread guides 44 may be adjustably mounted in apertures of a disc 46 carried by a sleeve 47 through which a core 48, such as an electrical conductor, is advanced. The sleeve 47 extends beneath the disc 46 a desired distance and this portion of the sleeve is tapered to guide the core to a position adjacent the point where it enters a central aperture of the needle carrier. The sleeve 47 also extends upwardly through a central aperture in a cross bar 50 and a sleeve 51 formed integral with the cross bar. The cross bar 50 is supported by the uprights 43 and extends outwardly at one end to form a journal 52 for a vertical shaft 53, the lower portion of the shaft being journaled in a bearing portion 54 integral with the frame 10. The shaft 53 is operatively connected to the power means for driving the knitting unit through belt wheels 56 and 57, which are operatively connected to each other by means of a belt 58. The belt wheel 56 is mounted upon the lower end of the shaft 53, while the belt wheel 57 is mounted upon and fixed to the hub of the bevelled gear 15.

A strand applying element 60 is rotatably mounted upon the sleeve 51 and has disposed thereon and fixed thereto a belt wheel 61, which is operatively connected to the shaft 53 through a belt 62 and a belt wheel 63, the latter being mounted upon the shaft 53. The element 60 has outwardly extending diametrically opposed arms 65 with trunnions 66 extending vertically therefrom to rotatably support spools 67 of strand material 68. In the present embodiment only one strand is shown being wound about the core, this strand being guided by an apertured pin 70 carried by the element 60. A similar pin is also provided for the other spool, the strand of which may be brought into use when the strand

of the first spool runs out. Another purpose of providing the diametrically opposed spool supporting arms for the element is to balance the element during rotation.

During the operation of the machine the shaft 17 is driven by its power means at a desired speed, causing rotation of the bevelled gear 15. Through this rotation the knitting unit and the strand applying element are operated simultaneously at desired relative speeds, but in view of the fact that the strand 68 is applied to the core prior to the forming of the knitted covering thereon operation of this portion of the machine will be considered first.

The rotary drive taken from the bevelled gear 15 may be followed through the wheel 57, the belt 58, the wheel 56, the shaft 53, the wheel 63, the belt 62, and the wheel 61, to the element 60. As a result of this driving means the element 60 is rotated clockwise, looking from the bottom thereof, and as the core 48 is moved longitudinally at a definite rate of speed by a suitable means (not shown) the strand 68 is wound spirally about the core, forming a spiral identifying rib about the core.

As the core with the spiral winding of the strand 68 thereon advances to the knitting unit, a covering is knitted on the core thus formed.

In the knitting unit the needle carrier 20 with the needle actuating levers 30 are rotated relative to the cams 33 and 34 and the thread guides 44. These moving portions are driven through the rotation of the shaft 12, which is connected to the bevelled gear 15 and is driven by the power means through the bevelled gear 16 and the power shaft 17.

During actuation of the knitting unit, which is caused by rotation of the tubular shaft 12, the needle carrier 20 with its needles 21 and associated levers 30 are rotated relative to the cams 33 and 34. Rotation of the cams causes movement of the levers, due to the contour of the lever engaging cam surfaces, to raise each needle to receive one of the threads at each thread position and lower the needles intermediate these thread positions, to thus form the covering on the conductor with the spiral winding of the strand 68 thereon.

The threads 40 are considerably smaller than the strand 68 and the covering formed by the threads will conform to the contour of the structure it is covering. This structure in the present instance is a core circular in cross section and having spiral ribs formed thereon by the strand 68. The completed article, therefore, as illustrated in Fig. 2, has spiral identifying ribs 75 disposed thereon in desired spaced formation so that they may be readily distinguished visually

in a properly lighted place or may be readily distinguished by the sense of touch in a dark or poorly lighted place.

The embodiment of the invention herein disclosed is illustrative only and may be widely modified and departed from in many ways without departing from the spirit and scope of the invention as pointed out in and limited only by the appended claims.

10 What is claimed is:

1. In an article forming machine, means to wind a strand on an electrical conductor while advancing to form an identifying rib thereon, and means to knit a covering over the ribbed conductor.
2. In an article forming machine, means to wind a strand on an electrical conductor while advancing to form an identifying rib thereon, threads smaller in size than the strand, and means to knit a covering of the threads over the ribbed conductor.
3. In an article forming machine, means to wind a strand on an electrical conductor while advancing to form an identifying rib thereon, threads smaller in size than the strand, and means to knit a covering of the threads over the ribbed conductor and in conformity therewith.
4. In an article forming machine, means to knit a covering on an electrical conductor while advancing, and means to position a member between the covering and the conductor to cause the covering to project outwardly from the conductor to form an identifying portion.
5. In an article forming machine, means to knit a covering on an electrical conductor while advancing, and means to position a member between the covering and the conductor to cause the covering to project outwardly from the conductor to form an identifying rib spirally positioned about the conductor.
6. In an article forming machine, a knitting unit to knit a covering on an electrical conductor while advancing, an element to wind a strand spirally about the conductor prior to the forming of the covering thereon to cause formation of an identifying rib in the covering, and means to actuate the element and unit simultaneously and at different speeds.
7. In an article forming machine, means to form a covering on an electrical conductor while advancing, and means to wind a strand spirally about the conductor prior to the forming of the covering thereon to cause the portions of the covering thereon to project outwardly beyond the other portions of the covering to form an identifying rib.

BEN K. FORD.
